(57) **CLAIM**

The ornamental design for a telematics device, as shown and described.

DESCRIPTION

The file of this patent contains at least one drawing or photograph executed in color. Copies of this patent with color drawings/photographs will be provided by the Office upon request and payment of the necessary fee.

FIG. 1 presents a perspective view showing front, left, and top sides of a telematics device.

FIG. 2 presents a front view of the telematics device.

FIG. 3 presents a back view of the telematics device.

FIG. 4 presents a top view of the telematics device.

FIG. 5 presents a bottom view of the telematics device, the bottom view comprising a view of a socket for an on-board diagnostic (OBD) port.

FIG. 6 presents a right side view of the telematics device.

FIG. 7 presents a left side view of the telematics device.

FIG. 8 presents a series of views of the telematics device, the series of views comprising a view of a socket for an on-board diagnostic (OBD) port in the rightmost view in the series of views.

FIG. 9 presents a perspective view showing front, right, and bottom sides of a telematics device.

FIG. 10 presents a perspective view showing front, left, and bottom sides of a telematics device, the perspective view comprising a view of a socket for an on-board diagnostic (OBD) port; and,

FIG. 11 presents a perspective view of front, right, and top sides of a telematics device.
